UNITED STATES PATENT OFFICE.

GOTTERFRID OLSON, OF MINNEAPOLIS, MINNESOTA, ASSIGNOR TO STEINER SALES COMPANY, OF SALT LAKE CITY, UTAH, A CORPORATION OF UTAH.

TOWEL CABINET.

Application filed August 2, 1926. Serial No. 126,540.

This invention relates to cabinets wherein provision is made for receiving a roll or web of clean towel to be dispensed over a delivering device to a position where it can be conveniently reached and used by a person standing in front of the cabinet, provision also being made for winding up the soiled web of towel on the takeup roll that is driven from the delivery device so that the delivery 10 of the clean web and the winding up of the soiled portion will be simultaneous and synchronous.

In such a cabinet, the web of soiled towel after being used, is dropped by the user 15 and frequently the soiled web will drop down over the front of the cabinet and trail upon the floor after repeated use of the cabinet and present an untidy and unsightly appearance in the toilet or other room where the cabinet 20 may be located.

The purpose, therefore, of my invention is to provide means set by the operation of drawing out and using the web of clean towel 25 for drawing the used portion of the towel into the cabinet immediately upon release of the web by the person using the towel.

A further object is to provide a simple, inexpensive mechanism which will be strong and durable and be operative for the purpose designed even though the pull of the user may be at one side of the towel web.

Other objects of the invention will appear from the following detailed description.

The invention consists generally in various constructions and combinations all as hereinafter described and particularly pointed out in the claims.

In the accompanying drawings, forming part of this specification,

Figure 1 is a vertical sectional view through a towel cabinet embodying my invention;

Figure 2 is a sectional view on the line 2-2 of Figure 1;

Figure 3 is a vertical sectional view on the line 3-3 of Figure 1;

Figure 4 is a vertical sectional view through the cabinet showing a modified form of the soiled towel takeup;

Figure 5 is a perspective view of the takeup device removed from the cabinet;

Figure 6 is a perspective view of a modified construction.

In the drawing, 2 represents an upright towel cabinet having supporting legs 3 and

a chamber 4 in the lower portion adapted to receive a roll or web of clean towel 5. The chamber 4 is separated from the upper portion of the cabinet by a partition 6. This partition extends upwardly along the rear of the cabinet and back of this partition through an opening 7 in the wall of which the clean web of towel is strung to the upper portion of the cabinet. At this point, I provide a delivery feed roll 8 having a roughened surface, preferably sanded, and over which the clean web of towel is stretched through a passage 9 provided between the feed roll and the top wall of the cabinet. A delivery device 10 adapted to be manipulated by the user of the towel is provided for controlling the length of the feed or the degree of movement of the feed roll with each operation. 11 is a second feed roll having a driving connection indicated by dotted lines with 75 the first named roll to be operated therefrom, the rolls being of substantially the same size and having the same peripheral speed, the second feed roll engaging the soiled web of towel that is wrapped around a takeup roll 80 12 that is vertically movable in slots 13. This takeup roll will only rest by gravity upon the roughened surface of the roll 11 and is driven thereby to wind up the soiled towel as the feed roll 11 is revolved through the operation of the feed roll 8. An opening 14 is provided in the front wall of the cabinet through which the user may have access to the towel web as it depends from the delivery feed roll and this towel web is held out of 85 contact with the takeup roll by a pivoted plate 15 mounted within the cabinet and limited in its downward movement by a stop 16.

The towel will be drawn out to the position indicated by dotted lines, by the person standing in front of the cabinet, and while the person using the cabinet should thrust the soiled portion of the towel back through the delivery opening, frequently he will not stop to do it and the web of soiled towel would 90 drop down on the outside of the cabinet, gradually increasing in length with each successive use until finally it would trail on the floor and present an unsightly appearance in the washroom.

To avoid this objection, I provide guideways 17 on each side of the cabinet and blocks 18 of a material suitably dense in character, such as metal to provide sufficient weight to slide quickly down to the bottom of 105 110

the guides when released. These blocks are preferably T-shaped in cross section as shown in Figure 2, and slide freely in the guides 17. Screw-eyes 19 are mounted in these blocks 5 and links 20 loosely connect the screw-eyes with pins 21 provided in the ends of a roller 22 around which the web of towel is passed before winding on the takeup roll. When the user draws the towel out of the cabinet for 10 wiping purposes, the roller 22 will be raised to the position shown in dotted lines in Figure 1 and when the user has finished wiping and releases the web, the weighted roller will quickly return to its normal position in the 15 lower portion of the guides and drag the soiled portion of the towel back into the cabinet where it will be hidden from view. A plate 23 is preferably mounted in the front wall of the cabinet between the blocks in which 20 the guides 17 are formed.

In Figure 4, a modified construction is shown which consists in providing a plate 24 having brackets 25 thereon in which a roller 26 is mounted, the plate 24 being of sufficient 25 weight to hold the roller at the bottom of the guides which correspond to those described with reference to Figure 2.

In Figure 6, another modification is shown which consists in providing pairs of anti-friction 30 wheels 27 at each end of the plate 24^a. These wheels bear on the outer walls of the guides to form anti-friction bearings for the sliding plate, preventing it from binding or cramping in the guides. In other respects, 35 the structure is substantially the same as described with reference to Figure 1.

I claim as my invention:

1. A towel cabinet adapted to receive a supply of clean towel, a delivery feed roll in 40 the upper portion of said cabinet over which the web of clean towel may be stretched, the front of the cabinet having a delivery opening, a second feed roll driven from said first named roll, a take-up around which the soiled towel may be wound and adapted to contact with said second feed roll, blocks mounted 45 to slide in vertical guideways in said cabinet, a roller having a tilting pivotal connection with said blocks and around which roller 50 the web of towel may be wound and stretched to said take-up roll, whereby drawing the towel web outwardly through said delivery

opening by the user raises said roller and blocks in said guideways, and the release of the towel web by the user allows said roller and blocks to return by gravity to their normal position and draws the soiled towel web within the cabinet. 55

2. A towel cabinet adapted to receive a web of clean towel, a feed delivery roll over which the web of clean towel may be stretched, the cabinet having a delivery opening adjacent said feed roll through which the user of the towel may grasp the clean web, a second feed 60 roll having a driving connection with said first named roll, a take-up roll around which the soiled towel may be wound for contact with said second feed roll, blocks mounted to slide vertically in said cabinet, a roller having pins in the ends thereof and links loosely 65 connecting said pins with said blocks, the web of towel being passed under said roller before connecting said pins with said blocks, the web of towel being passed under said roller before winding its end on the take-up roll, said roller and blocks being raised in said guideways 70 when the towel web is pulled out through said delivery opening by the user and the weight of the blocks and roller returning them to their normal position on said guideways and drawing the towel web back into the cabinet 75 through said delivery opening. 80

3. A towel cabinet having an opening in its upper front wall, and also having a middle compartment and a bottom compartment, a towel take up roll in the middle compartment and below the bottom of said opening, 85 the front wall of the cabinet extending upwardly to the bottom of said opening, a towel feed roll in the upper part of the cabinet, the cabinet having a chamber for a towel supply in the bottom compartment, the middle compartment having a back wall to separate the towel web as it passes from the towel supply chamber to the upper feed roll, a roller 90 having guides for reciprocation within the cabinet and below said opening and under which the towel passes as it advances to the take up roll, said roller serving to pull back into the cabinet through said opening the portion of towel web pulled out by the user 95 and thus keep the towel within the cabinet. 100

In witness whereof, I have hereunto set my hand this 29th day of July, 1926.

GOTTFRID OLSON.
